Primary Examiner — Terry A Wallace(74) *Attorney, Agent, or Firm* — Renner, Otto, Boisselle & Sklar, LLP(57) **CLAIM**

The ornamental design for a basket, as shown and described.

DESCRIPTION

FIG. 1 is a front elevation view of a basket showing my new design, it being understood that the rear elevation view, right side elevation view, and left side elevation view are omitted as they are identical to the front elevation view; FIG. 2 is a top, front, perspective view thereof; FIG. 3 is a top plan view thereof; and, FIG. 4 is a bottom plan view thereof.
